MINING APPARATUS

Louis A. Maxson, Claremont, N. H., assignor to
Sullivan Machinery Company, a corporation of
Massachusetts

Application February 19, 1931, Serial No. 516,953

91 Claims. (Cl. 262—28)

This invention relates to mining apparatus and more particularly, but not exclusively, to improvements in coal mining apparatus of the combined horizontal and shear cutter type adapted to 5 operate while supported and guided by a mine track.

An object of this invention is to provide an improved coal mining apparatus. Another object is to provide an improved coal mining apparatus 10 of the combined horizontal and shear cutter type. Another object is to provide in such an apparatus, improved adjustable kerf cutting mechanism operative to cut kerfs in parallel planes either horizontally or vertically. A further object is to provide an improved coal mining apparatus adapted 15 to operate while supported and guided by the mine track and having improved adjustable kerf cutting mechanism whereby shear kerfs may be inserted in the coal face at a plurality of locations between the ribs of the entry; and horizontal kerfs in a plurality of horizontal planes. Still another object is to provide an improved 20 mining apparatus of the track supported and guided type having improved adjustable kerf cutting mechanism whereby a shear kerf may be inserted in the coal face at the center of the entry and while the apparatus is mounted on and guided by a curved trackway. These and other objects and advantages of this invention will, however, hereinafter more fully appear.

In the accompanying drawings there is shown for purposes of illustration one form which the invention may assume in practice. In these drawings—

35 Fig. 1 is a plan view of the illustrative embodiment of the improved coal mining apparatus;

Fig. 2 is a side elevational view of the mining apparatus shown in Fig. 1;

40 Fig. 3 is an enlarged fragmentary plan view of the apparatus shown in Fig. 1, with parts shown in horizontal section to illustrate structural details;

Fig. 4 is a central longitudinally extending vertical sectional view taken substantially on line 45 4—4 of Fig. 3;

Fig. 5 is a detail sectional view taken on line 5—5 of Fig. 3;

Fig. 6 is a vertical sectional view taken substantially on line 6—6 of Fig. 1;

50 Fig. 7 is a horizontal sectional view taken substantially on line 7—7 of Figs. 2 and 6;

Fig. 8 is a vertical sectional view taken substantially on line 8—8 of Fig. 6;

Fig. 9 is a transverse vertical sectional view 55 taken substantially on line 9—9 of Fig. 1; and

Fig. 10 is a horizontal sectional view illustrating details of the mechanism shown in Fig. 9.

In this illustrative construction there is shown a coal mining apparatus of the wheel-mounted, track supported and guided type generally comprising a self-propelled truck 1 having wheels 2 adapted to run along a mine track 3. Mounted on the truck for adjustment into different elevated relative positions and for universal tilting movement relative to the truck is a substantially 10 horizontal turntable 4. Mounted on the turntable 4 for rotation relative thereto about an axis parallel to the turntable axis is a turntable 5. Mounted on the turntable 5 for rotation about an axis extending radially from the axial line of 15 the turntable is a cutter head 6 having pivotally mounted thereon about an axis perpendicular to the axial line of the cutter head a cutter bar 7. Suitable motor operated devices are provided for driving the truck wheels, for adjusting the turntable 4 into different elevated and tilted positions relative to the truck, for rotating the turntables 4 and 5 about their respective axes, for rotating the cutter head 6 about its axis, and for swinging the cutter bar 7 about its pivot relative to the 20 cutter head, as will hereinafter be described.

Suitable mechanism is provided for propelling the truck in either direction along the mine track at either a high transport or at a slow cutting speed. To accomplish these functions I have 30 illustrated herein a suitably modified mechanism from the prior art. This comprises a motor 10 carried at the rear end of the truck frame and having its armature shaft 11 connected in driving relation with a longitudinally extending shaft 35 12 (see Fig. 9). Fixed to the shaft 12 is a worm 13 meshing with a worm wheel 14. This worm wheel is connectible to a horizontal transversely extending shaft 15 by means of a multiple disc 40 clutch 16 of a usual design having suitable cam operating mechanism including a hand lever 17. Fixed to this transverse shaft 15 is a brake drum 18 having a usual brake band 19 which is also arranged to be controlled by the hand lever 17.

When this hand lever is swung in one direction 45 the friction clutch 16 is applied and the brake 18 released, and when swung in the opposite direction the brake is applied and the clutch released. Journaled on the shaft 15 is a spur gear 20 connectible with the shaft by a jaw clutch 50 member 21 splined to the shaft, and this gear meshes with a spur gear 22 fixed to a transverse shaft 23. Keyed to the shaft 15 is a spur pinion 24 meshing with a spur gear 25 fixed to a transverse shaft 26. Splined to the shaft 26 is a slid-

55

able pinion 27 adapted to mesh with a spur gear 28 herein fixed to a sleeve 29 rotatable with the spur gear 20 and likewise journaled on the shaft 15. If desired, operating mechanism may be provided for clutch 21 and the sliding pinion 27 so that when one is connected the other is released. As illustrated, secured to the shaft 23 is a chain sprocket 33 connected by a usual endless chain connection 31 to a chain sprocket secured to the rear truck axle. The front and rear truck axles are connected together by a usual chain and sprocket connection 32. From the foregoing description it will be evident that when the jaw clutch 21 is shifted to connect the spur gear 20 to the shaft 15, and the pinion 27 is out of mesh with the gear 28, the truck wheels may be driven from the motor 10 at a relatively high speed through worm gearing 13, 14, friction clutch 16, shaft 15, spur gearing 20, 22 and the chain and sprocket connections 31, 32. It will also be evident that when the jaw clutch 21 is in its released position, that is, when the spur gear 20 is disconnected from the shaft 15 and the spur pinion 29 is in meshing engagement with the gear 28, the truck wheels may be driven at a relatively slow speed appropriate for cutting through the reduction gearing 24, 25, 27, 28. Upon reversal of the motor 10, the truck wheels may be driven to propel the apparatus in the reverse direction at either a relatively high or a relatively low speed.

Now referring to the supporting structure for the turntable 4 and the devices for elevating and universally tilting the same, it will be noted that supported on the truck directly above the truck wheels is an annular or ring-shaped supporting frame 35 having attached thereto a plurality of, herein three, depending brackets 36, the lower ends of which are shaped to engage respectively with upstanding guide members 37 which are secured to the truck frame and which serve to prevent substantial lateral movement of the annular frame 35 and attached parts relative to the truck frame. Secured to the feet of these depending brackets 36 are screw nuts 38 (see Fig. 5) which are threadedly engaged with vertical screws 39 supported at their upper ends by the upstanding guide members 37 and at their lower ends in step bearings 40 formed in bearing brackets 41 attached to the bottom of the truck frame. It will be noted that the screw nuts are so connected to the feet of the depending brackets 36 as to permit a slight relative rocking movement between the parts for a purpose to be hereinafter described. The three sets of screws and guide members constitute upright supports for the annular supporting frame 35, and the latter can be adjusted vertically in parallelism or for universal tilting movement relative to the horizontal by suitable rotation of the screws 39. Rotatably mounted upon each of the screws 39 at its lower end is a chain sprocket 42 and these sprockets are driven by an endless chain 43. Idler sprockets 44 and 45 serve to guide the chain 43 relative to the chain sprockets 42, the sprocket 45 being adjustable to vary the tension of the chain. As shown in Fig. 5, the chain sprockets 42 each have formed thereon clutch teeth 46 with which similar teeth on clutch members 47 splined to the lower end of the screws, are engageable. The screws extend downwardly through openings in the top plate 48 of the truck frame. The clutch members 47 are each provided with a groove 49 in engagement with a shipper arm 50 attached to a vertical operating shaft 51. The shafts 51

extend upwardly through the top plate 48 and they are each provided with a conveniently located handle 52 by which the movement of the clutch members 47 may be controlled. It will thus be seen that when all the clutches 47 are in a position to connect the chain sprockets to the screws the latter may be simultaneously rotated to effect movement of the annular frame 35 for supporting the turntable 4 together with the cutting mechanism supported thereby into different elevated positions relative to the truck frame. It will also be noted that by releasing certain of these clutches and connecting certain others, the screws may be operated to effect universal tilting movement of the turntable supporting frame relative to the horizontal to change the angle in altitude of the cutting mechanism. The mechanism for driving the screws 39 from the motor 10 herein comprises a bevel pinion 53 (see Fig. 9) journaled on the shaft 15 and connectible to the shaft by the jaw clutch member 21. This bevel pinion meshes with a bevel gear 54 fixed to a vertical shaft 55 while keyed to the lower end of this shaft is a chain sprocket 56 which engages and drives the endless chain 43. This particular turntable supporting and adjusting mechanism may obviously be modified or replaced by other designs, the design herein disclosed being one from the prior art.

The turntable 4 supported by the annular supporting frame 35 is, in the present instance, in the form of a circular casting which constitutes the main frame for supporting the cutting mechanism. This casting forms the turntable rotatable about the center of the annular frame 35 and is guided for rotative movement in the frame by a depending annular flange 57 fitting the interior periphery of the annular frame; and by a peripheral flange 58 overlying the top surface of the annular frame. If desired, suitable anti-friction rollers of any conventional design may be provided between the turntable 4 and the annular supporting frame 35 for reducing the friction between the parts. In the outer edge of the turntable casting is formed a series of notches 59, and cooperating with these notches is a slidable locking plate 60 mounted in a suitable guideway formed within a bracket 61 attached to the annular supporting frame 35. This locking member, when in its innermost position, is adapted to project within one of the notches 59 to lock the turntable 4 against rotation relative to the annular supporting frame 35. Motor operated devices are employed for rotating the turntable 4 relative to its annular supporting frame, and herein comprise a motor 66, which may be of the reversible electric type, suspended beneath the turntable within the lateral limits of the supporting frame 35 and having its armature shaft 66 horizontally disposed and extended transversely across the turntable. Fixed to the armature shaft is a bevel pinion 67 meshing with a bevel gear 68 fixed to a vertical shaft 69 as shown in Fig. 4. Fixed to the shaft 69 is a spur gear 70 meshing at its opposite sides, as shown in Fig. 3, with spur gears 71 and 72. Rotatable with the spur gear 71 is a worm 73 meshing with a slow speed worm wheel 74. This worm wheel is connectible by a usual multiple disc clutch 75, having any suitable type of operating means, to a transverse shaft 76. Fixed to this shaft is a worm 77 meshing with a worm wheel 78 keyed to a vertical shaft 79. As shown in Fig. 4, rotatably supported on the shaft 79 is a spur gear 80 projecting through a slot 81 cut

through the depending flange 57 and meshing with internal gear teeth 82 herein cut in the inner wall of the annular supporting frame 35. The gear 80 is connectible to the shaft 79 by a 5 multiple disc clutch 83 of a usual design having any suitable operating means. Rotatable with the spur gear 72 is a worm 84 (Fig. 3) meshing with a fast speed worm wheel 85 having its teeth oppositely inclined from the teeth of 10 the worm wheel 74 and operative upon application of a multiple disc clutch 86 to effect drive of the shaft 76 at a fast speed in a direction opposite from the slow speed drive. It will thus be seen that when the gear 80 is connected to 15 the shaft 79 by the clutch 83 and one or the other of the clutches 75, 86, is applied, the turntable 4 may be rotated relative to the annular supporting frame 35 at a relatively high positioning speed in one direction or at a relatively 20 low speed appropriate for cutting in the opposite direction. In its general arrangement this turntable rotating mechanism corresponds closely with a prior design.

As previously mentioned, mounted on the turntable 4 is a turntable 5 and this turntable comprises, in the particular form shown herein, a circular casting 90 having a depending flange fitting an annular member or ring 91 secured as by screws 92 to the turntable 4. Attached to the turntable casting 90 is a thrust ring 93 underlying the ring 91 for maintaining the turntable 5 in position. The turntable casting 90 is provided with a radial flange 94 overlying the ring 91 and rotatably mounted on a suitable ring bearing 95. For locking the turntable 5 in its different adjusted positions about its axis relative to the turntable 4, there is provided a plurality of recesses 96 formed in the flange 94 of the turntable casting, and cooperating with these recesses is a pivoted latch or dog 97 supported by a bracket 98 attached to the turntable 4. Devices driven by the motor 65 are employed for rotating the turntable 5 about its axis, and herein comprise a chain sprocket 99 30 rotatably supported on the lower end of the shaft 79 (see Fig. 4) and connectible to the shaft by means of a multiple disc clutch 83^a similar to the clutch 83 and having similar operating means. The sprocket 99 is connected by an endless chain 100 to a sprocket 101 fixed to the lower end of a vertical shaft 102 suitably journaled within the turntable casting of the turntable 4. Fixed to the upper end of the shaft 102 is a spur gear 103 meshing with the teeth of an internal gear 104, herein formed integral with the turntable casting 90. It will thus be seen that when the sprocket 99 is connected to the shaft 79 by the clutch 83^a and when one or the other of the friction clutches 75, 86 is applied, the turntable 5 may be rotated about its axis at a fast positioning speed in one direction and at a relatively slow speed in the opposite direction while the turntable 4 remains stationary. It will also be seen that when friction clutches 83 and 83^a 45 are appropriately controlled the turntables 4 and 5 may be simultaneously rotated about their respective axes in opposite directions and at substantially the same angular speeds.

Now referring to the cutting mechanism supported by the turntable 5 and the supporting structure therefor, it will be observed that the turntable casting 90 is provided with an integral box-like extension or arm 105 extending radially from the axial line of the turntable 5 and this arm is rigidly braced with respect to the turn-

table casting 90 by horizontal webs 106 and herein overlies the annular frame 35 and overhangs the forward end of the truck, as shown in Fig. 4. Formed integral with this extension frame or arm at its outer extremity is a circular flange 107 arranged in a substantially vertical position and rigidly braced with respect to the arm by means of vertical webs 108. This circular flange 107 has attached thereto a cylindrical bearing sleeve 109 (see Figs. 6 and 7) and rotatably mounted on this sleeve is a cylindrical supporting frame 110 having an inwardly directed annular retaining flange 111 and attached to the frame 112 of the cutter head 6. Mounted on the cutter head frame for rotation about an axis at right angles to the axis of the cutter head is a cylindrical supporting frame 113 rotatably mounted in a bore 114 formed in the cutter head frame. A thrust ring 115 attached to the cutter head frame retains the frame 113 in its bore. 15 Attached to the frame 113 is a support or hanger 116 which carries the cutter bar 7. Mounted for orbital movement on the margin of the cutter bar 7 is a usual cutter chain 117 carrying usual cutter bits. 20

The mechanism for driving the cutter chain 117 comprises a bevel gear 118 (see Fig. 4) meshing with the gear 67 and fixed to a horizontal shaft 119. Fixed to the opposite end of this shaft is a bevel gear 120 meshing with a 25 bevel gear 121 fixed to a vertical shaft 122 having its axis coincident with the axis of the turntable 5. The shaft 122 drives a bevel gear 123 which in turn meshes with and drives a bevel gear 124 fixed to a horizontal shaft 125 herein 30 extending radially from the axial line of the turntable 5. Keyed to the outer end of the shaft 125 is a spur pinion 126 meshing with a spur gear 127 fixed to a horizontal shaft 128 extending along the axis of the rotatable cutter head 40 6. Herein fixed to the forward end of the shaft 128 as shown in Fig. 6 is a bevel gear 129 meshing with and driving a bevel gear 130 (see also Fig. 6) journaled on a shaft 131 herein arranged with its axis coincident with the axis of bar 45 swing. The shaft 131 has fixed thereto and drives a sprocket 132 which in turn engages and drives the cutter chain 117. The gear 130 is connectible to the shaft 131 by a sliding jaw clutch 133 having usual clutch shipper 134 operated by a handle 135. It will thus be seen that irrespective of the adjusted position of the turntable 5 and cutter head 6 relative to the turntable 4, the cutter chain 117 may at all times be driven, and that by simply releasing 50 the clutch 133 the cutter chain may remain idle during running of the motor 65.

Now referring to the mechanism for effecting swinging of the cutter bar 7 about its pivotal axis relative to the cutter head, it will be noted that 60 rotatable with the gear 130 (Fig. 6) is a bevel gear 136 constantly meshing with the reversely rotatable bevel gears 137, 138 (Figs. 7 and 8) loosely journaled on a transverse shaft 139. The reverse bevels are selectively connectible to the shaft 139 by means of multiple disc clutches 140 and 141 of a usual design operated by a suitable shipper mechanism 142 controlled by a handle 143. Connectible to the shaft 139 is a worm 144 meshing with a worm wheel 145 fixed to a shaft 70 146 arranged parallel with the shaft 139. Fixed to the shaft 146 is a spur pinion 147 meshing with the teeth of an internal gear 148 herein formed integral with the cylindrical supporting frame 113 for the cutter bar 7. The worm 75

144 is connectible to the shaft 139 by a sliding clutch element 149 and cooperating clutch elements carried by the worm and shaft respectively. The sliding clutch element 149 is provided with usual shipper mechanism 150 operated by a handle 151. It will thus be seen that depending upon which one of the friction clutches 140, 141, is applied the cutter bar may be swung about its pivot relative to the cutter head at a speed appropriate for cutting in either of opposite directions. The mechanism for rotating the cutter head 6 about its axis herein comprises a worm 152 connectible to the shaft 139 and meshing with a worm wheel 153 fixed to a longitudinally extending shaft 154 arranged parallel with the shaft 128. This shaft carries a pinion 155 meshing with the teeth of an internal gear 156 herein formed integral with the cylindrical bearing sleeve 109 on which the cutter head 6 is rotatably mounted. The worm 152 is connectible to the shaft 139 by a sliding clutch element 157 cooperating with clutch elements carried by the worm and shaft respectively. This sliding clutch element is provided with usual shipper mechanism 158 operated by a handle 159. It will, therefore, be evident that the cutter head 6 may be rotated about its axis in either of opposite directions under the control of the friction clutches 140, 141. The worm gears 144, 145 and 152, 153 of the bar swinging and head rotating mechanisms are self-locking and upon release of the clutches 149, 157 maintain automatically the cutter bar and head in their respective positions of adjustment.

35 Electrical energy may be conducted to the electrical controlling apparatus for the motors 10 and 65 through a usual flexible conductor cable 160 wound upon a cable reel 161 supported at the rear end of the truck as shown in Figs. 1 and 2. This cable reel is driven by the motor 10 through the following connections: As mentioned above, journaled on the shaft 15 is a sleeve 29 integral with the spur gear 20 (see Fig. 9) and rotatable therewith at either a fast or a slow speed through the gear trains above referred to. Splined to this sleeve is a suitable jaw clutch 162 having clutch teeth engageable with clutch teeth formed upon a driving pulley 163 journaled on the sleeve 29. This pulley 163 is connected by a belt 164 to a pulley 165 secured to the cable reel. It will be evident that as the truck wheels are driven to propel the apparatus in either direction along the mine track, the cable reel 161 may be also rotated to wind in or pay out the conductor cable in a manner well understood in the art.

60 The preferred mode of operation of the improved mining apparatus will now be described: The apparatus is propelled about the mine forwardly along the mine track at a relatively fast transport speed through the truck driving gear 13, 14, 20, 22 driven by the motor 10. When the apparatus is traveling about the mine, the turntables 4 and 5, the cutter head 6 and the cutter bar 7 are disposed in their transport position as shown in Figs. 1 and 2. When the working face is reached the fast truck wheel drive is disconnected from the motor 10 by releasing the friction clutch 16 and the jaw clutch 21. If it is desired to make a horizontal cut in the coal face in accordance with the arcweld method of cutting, the operator first connects the clutch 149; and upon application of the friction clutch 140 the cutter bar is swung about its pivot relative to the cutter head from the central longitudinal position

shown in Fig. 1 to a position where the tip end of the cutter bar is disposed adjacent the coal face at the right hand rib of the entry, the clutch 140 thereafter being released. The self-locking worm gearing 144, 145 holds the cutter bar in this position. The clutch 133 is then shifted to a position to connect the shaft 121 to the driving gear 130 thereby connecting the cutter chain 117 in driving relation with the motor 65, and as a result the cutter chain is rapidly circulated about the margin of the cutter bar 7. The pinion 27 of the truck driving mechanism is then slid into meshing engagement with the gear 28 and, upon application of the friction clutch 16, the apparatus is propelled bodily along the mine track at a cutting speed thereby to effect sumping of the cutter bar within the coal, the clutch 16 thereafter being released. The brake 19 is then applied, holding the truck wheels against rotation thereby preventing movement of the apparatus relative to the mine track. The friction clutch 141 of the bar swinging mechanism is then applied and the cutter bar swung at a relatively slow cutting speed to effect its transverse swinging cut across the coal face, the clutch 141 and brake thereafter being released. When the tip end of the bar is positioned in the left hand rib of the entry and the swinging cut completed, the motor 10 is reversed and upon application of the friction clutch 16, the apparatus is propelled bodily rearwardly along the mine track at a slow cutting speed to effect withdrawal of the cutter bar from the coal thereby completing the kerf in the coal. After the horizontal cut has been completed the sliding gear 27 is shifted out of mesh with the gear 28 and the clutch 21 shifted to a position to connect the gear 26 to the shaft 15, and upon application of the friction clutch 16 the apparatus is propelled bodily rearwardly along the mine track at a relatively high transport speed to another working place. It will of course be understood that instead of swinging the cutter bar about its pivot relative to the cutter head 6 during the transverse swinging cut the bar may be swung with the turntable 4 about the turntable axis as a pivot under control of the friction clutch 83 and under certain conditions the bar may be swung about the axis of the turntable 5 under the control of clutch 83a.

45 If it is desired to insert horizontal kerfs in the coal face at different elevations this may be accomplished simply by shifting the clutch members 49 of the turntable elevating mechanism downwardly to connect the chain sprockets 42 to the adjusting screws 39 and sliding clutch 21 to connect the bevel 53 to the shaft 15. The motor 10 is then rotated in the proper direction and, upon application of the friction clutch 16, the turntable 4, together with cutting mechanism carried thereby, is adjusted vertically relative to the truck. If it is desired to tilt the turntable 4 relative to the horizontal to change the angle in altitude of the cutting mechanism, this may be accomplished by disconnecting certain of the adjusting screws from the motor while the others are rotated thereby. For instance, if it is desired to tilt the tip end of the cutter bar downwardly this may be accomplished by disconnecting the clutches for the front elevating screws 39 while the rear elevating screw is connected to the motor thereby causing the rear edge of the turntable to be tilted upwardly. Conversely, if it is desired to tilt the tip end of the cutter bar upwardly the rear elevating screw may be disconnected from the motor while the front elevating

- Screws are rotated thereby causing the forward edge of the turntable to be tilted upwardly. It will also be noted that upon suitable adjustment of the elevating screws the turntable 4 may be universally tilted into different angular positions about transverse, longitudinal or any desired intermediate axes, thereby enabling the cutter bar to be positioned to accommodate itself to different mining conditions. If it is desired to insert horizontal cuts adjacent the mine roof the operator connects the clutch 157 and upon application of one or the other of the friction clutches 148, 141, the cutter head 6 may be rotated about the head axis until the cutter bar assumes a horizontal top cutting position, the clutches thereafter being released. When the cutter bar is in this top cutting position the turntable 4 may be elevated along the elevating screws 39 to its uppermost position relative to the truck. A shear or vertical cut may be inserted in the coal face simply by connecting the clutch 157 and applying one or the other of the friction clutches 148, 141 thereby effecting rotation of the cutter head about its axis to bring the cutter bar 7 into a position to swing vertically, the clutches thereafter being released. If it is desired to insert a shear cut at the center of the entry, the cutter head is shifted laterally into the position indicated in dotted lines in Fig. 1. To so position the cutter bar the locks 60 and 97 for the turntables 4 and 5 are released and the gear 80 and the sprocket 99 are connected to the shaft 79 by the clutches 83 and 83^a and upon application of the proper friction clutch 75, 86 of the turntable rotating means, the turntable 4 is rotated relative to the truck in a counterclockwise direction, as viewed in Fig. 1 while the turntable 5 is rotatable, if the drive of turntable 4 be appropriately slipped, simultaneously at substantially the same angular speed in a clockwise direction, thereby moving the turntable 5 from the full line position shown in Fig. 1 to the dotted line position in that figure, the friction clutches thereafter being released. The turntables 4 and 5 are then locked against rotation by their respective locking elements 60 and 97. The cutter bar is swung upwardly, sumped in, swung downwardly in its plane, and withdrawn from the coal in substantially the same manner as in the horizontal cut described above. If it is desired to insert a shear cut at the left hand rib of the entry this may be accomplished by rotating the cutter head 6 about its axis until the cutter bar assumes a vertical cutting position opposite with respect to the head axis from that shown in dotted lines in Fig. 1. Also it will be evident that by suitably adjusting the turntable 4 and 5 about their respective axes and by adjusting the cutter bar about the axis of the cutter head 6 it is possible to insert shear cuts in the coal face at any desired location between the ribs of the entry. It will also be noted that when the parts are in the dotted line position indicated in Fig. 1 and it is desired to insert a shear cut in the coal face while the apparatus is supported and guided by a curved mine track, it is possible to sump in the cutter bar and withdraw the bar from the coal by permitting the turntable 4 to rotate freely as the truck moves bodily forwardly and rearwardly along the curved mine track, the free movement of the turntable preventing the cutter bar from being cramped in the kerf. As a result of this invention it will be noted that an improved coal mining apparatus is provided which is adapted to cut horizontal kerfs in a plurality of parallel planes and also to make shear or vertical cuts at any desired location between the ribs of the entry. It will further be noted that, due to the plurality of turntable mountings on the truck for the cutting mechanism, it is possible to adjust the cutter bar to insert shear cuts in the coal within a comparatively wide range, and also to permit the cutter bar to insert a shear cut at the center of the entry while the apparatus is supported and guided on a curved mine track. It will further be noted that an improved coal mining apparatus is provided wherein the adjusting mechanism for the kerf cutting mechanism is extremely flexible, it being possible to operate the apparatus adjacent the floor and roof of the entry, at the center of the entry, and to make shear cuts at a plurality of locations between the ribs of the entry, thereby enabling the apparatus to accommodate itself to a comparatively wide range of cutting conditions. These and other uses and advantages of the improved mining apparatus will be clearly apparent to those skilled in the art.
- While there is in this application specifically described one form which this invention may assume in practice, it will be understood that this form of the same is shown for purposes of illustration and that the invention may be modified and embodied in various other forms without departing from its spirit or the scope of the appended claims.
- What I claim as new and desire to secure by Letters Patent is:
1. In a mining apparatus, a portable base, a support mounted on said base for swinging movement relative thereto about a normally vertical axis, a second support mounted on said first support for swinging movement relative thereto about a parallel axis lying within the lateral limits of said first support, said second support overlying said first support and overhanging the front end of said base, a kerf cutter pivotally mounted on the outer extremity of said second support for swinging movement relative thereto, and means for swinging said supports about their respective axes and for swinging said cutter bar about its pivot.
  2. In a mining apparatus, a portable base, a support mounted on said base for swinging movement relative thereto about a normally vertical axis, a second support mounted on said first support for swinging movement relative thereto about a parallel axis, said second support overhanging the front end of said base, a kerf cutter pivotally mounted on the outer extremity of said second support for swinging movement relative thereto, means for swinging said supports about their respective axes and for swinging said cutter bar about its pivot, and a motor carried by said first support for driving said support swinging means and the means for swinging said cutter bar.
  3. In a mining apparatus, a portable base, a support mounted on said base for adjustment relative thereto into different elevated positions and for rotation relative to the base about a normally vertical axis, a second support mounted on said first support for rotation relative thereto about a parallel axis, said second support overhanging the front end of said base, a kerf cutter pivotally mounted on the outer extremity of said second support for swinging movement relative thereto, means for adjusting the elevation of said first support relative to the base, and means for swinging said supports about their re-

spective axes and for swinging said kerf cutter about its pivot.

4. In a mining apparatus, a portable base, a support mounted on said base for adjustment relative thereto into different elevated positions and for rotation relative to the base about a normally vertical axis, a second support mounted on said first support for rotation relative thereto about a parallel axis, said second support overhanging the front end of said base, a kerf cutter pivotally mounted on the outer extremity of said second support for swinging movement relative thereto, means for adjusting the elevation of said first support relative to the base, means for swinging said supports about their respective axes and for swinging said kerf cutter about its pivot, and a motor carried by said first support for driving said support swinging means and the means for swinging said kerf cutter.

20. 5. In a mining apparatus, a portable base, a support mounted on said base for adjustment relative thereto into different elevated positions and for rotation relative to the base about a normally vertical axis, a second support mounted on said first support for rotation relative thereto about a parallel axis, said second support overhanging the front end of said base, a kerf cutter pivotally mounted on the outer extremity of said second support for swinging movement relative thereto, means for adjusting the elevation of said first support relative to the base, means for swinging said support about their respective axes and for swinging said kerf cutter about its pivot, a motor carried by said first support for driving said support swinging means and the means for swinging said kerf cutter, and a motor carried by the portable base for driving the means for adjusting the elevation of said first support.

40. 6. In a mining apparatus, a movable base, a support mounted on said base for swinging movement relative thereto about a normally vertical axis, a second, elongated, support mounted on said first support for independent rotation relative thereto about a parallel axis, normally disposed forwardly of said first mentioned vertical axis, a substantially horizontally extending cutter bar, mounting means for the cutter bar in connection with the second support whereby the bar is movable relative to the support about a plurality of rectangularly related axis of which one is substantially on the horizontal, means operable to swing said supports about their respective axes, and means operable to move the cutter bar about said plurality of rectangularly related axes.

45. 7. In a mining apparatus, a movable base, a support mounted on said base for swinging movement relative thereto about a normally vertical axis, a second support mounted on said first support for rotation relative thereto about a parallel axis, a substantially horizontally extending cutter bar, mounting means for the cutter bar in connection with the second support whereby the bar is movable relative to the support about a plurality of rectangularly related axes, of which one is substantially on the horizontal, means operable to swing said supports about their respective axes, means operable to move the cutter bar about said plurality of rectangularly related axes, and a motor on said first support for driving the support swinging means and the cutter bar moving means.

50. 8. In a mining apparatus, a truck adapted to travel over a mine track, a turntable supported on said truck for rotation relative to said truck

on a normally vertical axis, a second turntable mounted on said first turntable for rotation relative thereto about a parallel axis, an arm fixed to said second turntable and projecting horizontally therefrom, a kerf cutter supported by said arm for movement relative thereto about a plurality of rectangularly related axes of which one is substantially on the horizontal, means operable to rotate the turntables, and means operable to move the cutter bar about said plurality of rectangularly related axes.

5. 9. In a mining apparatus, a truck adapted to travel over a mine track, a turntable supported on said truck for rotation relative to said truck on a normally vertical axis, a second turntable mounted on said first turntable for rotation relative thereto about a parallel axis, an arm fixed to said second turntable and projecting horizontally therefrom, a kerf cutter supported by said arm for movement relative thereto about a plurality of rectangularly related axes of which one is substantially on the horizontal, means operable to rotate the turntables, means operable to move the cutter bar about said plurality of rectangularly related axes, and a motor on the first turntable for driving the turntable swinging means and the cutter bar moving means.

10. 10. In a mining apparatus, a movable base, a support mounted on said base for swinging movement relative thereto about a normally vertical axis and for adjustment bodily relative to said base, a second support mounted on said first support for swinging movement relative thereto about a parallel axis, a substantially horizontally extending cutter bar, mounting means for the cutter bar in connection with the second support whereby the bar is movable relative to the support about a plurality of rectangularly related axes of which one is substantially on the horizontal, means operable to adjust bodily said first support relative to the base, means operable to swing the supports about their respective axes, and means operable to move the cutter bar about said plurality of rectangularly related axes.

40. 11. In a mining apparatus, a movable base, a support mounted on said base for swinging movement relative thereto about a normally vertical axis and for adjustment bodily relative to said base, a second support mounted on said first support for swinging movement relative thereto about a parallel axis, a substantially horizontally extending cutter bar, mounting means for the cutter bar in connection with the second support whereby the bar is movable relative to the support about a plurality of rectangularly related axes of which one is substantially on the horizontal, means operable to adjust bodily said first support relative to the base, means operable to swing the supports about their respective axes, means operable to move the cutter bar about said plurality of rectangularly related axes, and a motor on said first support for driving the support swinging means and the cutter bar moving means.

45. 12. In a mining apparatus, a movable base, a support mounted on said base for swinging movement relative thereto about a normally vertical axis and for adjustment bodily relative to said base, a second support mounted on said first support for swinging movement relative thereto about a parallel axis, a substantially horizontally extending cutter bar, mounting means for the cutter bar in connection with the second support whereby the bar is movable relative to the support about a plurality of rectangularly related axes.

50. 75.

- related axes of which one is substantially on the horizontal, means operable to adjust bodily said first support relative to the base, means operable to swing the supports about their respective axes, 5 means operable to move the cutter bar about said plurality of rectangularly related axes, a motor on said first support for driving the support swinging means and the cutter bar moving means, and a motor on said base for driving said 10 adjusting means for bodily adjusting said first support.

13. In a mining apparatus, a truck adapted to travel over a mine track, a turntable, means supporting said turntable on said truck for rotation relative to the truck on a normally vertical axis and also for bodily adjustment relative to the truck, a second turntable mounted on said first turntable for rotation relative thereto about a parallel axis, an arm fixed to the second turntable and projecting horizontally therefrom, a kerf cutter supported by said arm for movement relative thereto about a plurality of rectangularly related axes of which one is substantially on the horizontal, means operable to adjust bodily said 15 first turntable relative to the truck, means operable to rotate said turntables about their respective axes, and means operable to move the cutter bar about said plurality of rectangularly related axes.

14. In a mining apparatus, truck adapted to travel over a mine track, a turntable, means supporting said turntable on said truck for rotation relative to the truck on a normally vertical axis and also for bodily adjustment relative to the truck, a second turntable mounted on said 20 first turntable for rotation relative thereto about a parallel axis, an arm fixed to the second turntable and projecting horizontally therefrom, a kerf cutter supported by said arm for movement relative thereto about a plurality of rectangularly related axes of which one is substantially on the horizontal, means operable to adjust bodily said first turntable relative to the truck, means operable to rotate said turntables about their respective axes, and means operable to move the cutter bar about said plurality of rectangularly related axes.

15. In a mining apparatus, a truck adapted to travel over a mine track, a turntable, means supporting said turntable on said truck for rotation relative to the truck on a normally vertical axis and also for bodily adjustment relative to the truck, a second turntable mounted on said 25 first turntable for rotation relative thereto about a parallel axis, an arm fixed to the second turntable and projecting horizontally therefrom, a kerf cutter supported by said arm for movement relative thereto about a plurality of rectangularly related axes of which one is substantially on the horizontal, means operable to adjust bodily said first turntable relative to the truck, means operable to rotate said turntables about their respective axes, and means operable to move the cutter bar about said plurality of rectangularly related axes.

16. In a mining apparatus, a portable base, a support mounted on said base for swinging movement relative thereto about a normally vertical axis and also for universal tilting movement rel-

ative to the base, a second support mounted on said first support for swinging movement relative thereto about a parallel axis, a substantially horizontally extending cutter bar, mounting means for the cutter bar in connection with the second support whereby the bar is movable relative to the support about a plurality of rectangularly related axes of which one is substantially on the horizontal, means operable to tilt the first support, means operable to swing both supports about their respective axes, and means operable to move the cutter bar about said plurality of rectangularly related axes.

17. In a mining apparatus, a portable base, a horizontal turntable mounted on said base for rotation about a vertical axis and for universal tilting movement relative to the horizontal, an arm structure pivotally mounted upon a substantially upright axis on said turntable and adjustable therewith and relative thereto, and kerf cutting mechanism carried at the outer extremity of said arm structure and adjustable relative thereto into horizontal and vertical cutting positions.

18. In a mining apparatus, a portable base, a horizontal turntable mounted on said base for rotation relative thereto about a vertical axis, an arm structure pivotally mounted upon a substantially upright axis on said turntable for swinging movement relative thereto about an axis located adjacent the forward end of said base and overhanging said base, and kerf cutting mechanism carried at the outer overhanging extremity of said arm structure and adjustable relative thereto into horizontal and vertical cutting positions.

19. In a mining apparatus, a portable base, a support mounted on said base for adjustment relative thereto into different elevated positions and for rotation about a vertical axis, an arm structure pivotally mounted upon a substantially upright axis on said support for swinging movement relative thereto and extending forwardly in advance of said base, and kerf cutting mechanism mounted on the outer extremity of said arm structure and adjustable relative to said arm structure into horizontal and vertical cutting positions.

20. In a mining apparatus, a portable base, a kerf cutter swingable to cut a kerf in a vertical plane, mounting means on said base for adjusting said kerf cutter to cut vertical kerfs in parallel planes including a plurality of relatively adjustable supports swingable relative to said base about parallel vertical axes, and motor operated devices including a motor mounted on one of said swingable supports for swinging said supports about their respective axes.

21. In a mining apparatus, a portable base, a kerf cutter swingable to cut a kerf in a vertical plane, mounting means on the base for adjusting said kerf cutter to cut vertical kerfs in parallel planes including a support mounted on said base for swinging movement relative thereto about a vertical axis, and a support mounted on said first support for swinging movement relative thereto about a parallel axis, said second support having said kerf cutter mounted thereon for swinging movement relative thereto, and motor operated devices including a motor mounted on one of said swingable supports for swinging said supports about their respective axes.

22. In a mining apparatus, a portable base, a support mounted thereon for swinging movement relative thereto about a vertical axis, a second, elongated, support mounted on said first sup-

- port for independent swinging movement relative thereto about a normally more-forwardly-disposed parallel axis, a kerf cutter, means for mounting said kerf cutter on said second support 5 for adjustment relative thereto into parallel cutting positions, and means for swinging said supports about their respective axes to position said kerf cutter into parallel planes laterally relative to said base.
- 10 23. In a mining apparatus, a portable base, a support mounted thereon for swinging movement relative thereto about a vertical axis, a second, elongated, support mounted on said first support for independent swinging movement relative thereto about a normally more-forwardly-disposed parallel axis, a kerf cutter, means for mounting said kerf cutter on said second support for adjustment relative thereto about a horizontal axis to position said kerf cutter in parallel cutting planes at either side of said horizontal axis, and means for swinging said supports about their respective axes to position said kerf cutter into parallel planes laterally relative to said base.
- 15 24. In a mining apparatus, a portable base, a support mounted on said base for swinging movement relative thereto about a normally vertical axis, a second support mounted on said first support for swinging movement relative thereto about a parallel axis, said second support overhanging the front end of said base, a kerf cutter pivotally mounted on the outer extremity of said second support for swinging movement relative thereto, means for swinging said supports about their respective axes and for swinging said cutter bar about its pivot, and a motor carried by one of said supports for driving said support swinging means and the means for swinging said cutter bar.
- 20 25. In a mining apparatus, a portable base, a horizontal turntable mounted on said base for rotation relative thereto about a vertical axis, a second turntable mounted on said first turntable for rotation relative thereto and to said base about a parallel axis, a cutter head mounted on said second turntable for rotation relative thereto about a horizontal axis, a kerf cutter pivotally mounted on said cutter head, and motor operated devices for rotating said turntables about their respective axes to move said cutter head into different lateral positions relative to said base.
- 25 26. In a mining apparatus, a portable base, a horizontal turntable mounted on said base for rotation relative thereto about a vertical axis, a second turntable mounted on said first turntable for rotation relative thereto and to said base about a parallel axis, a cutter head mounted on said second turntable for rotation relative thereto about a horizontal axis, a kerf cutter pivotally mounted on said cutter head, and a motor mounted on one of said turntables for rotating said turntables about their respective axes.
- 30 27. In a mining apparatus, a portable base, a support mounted on said base for tilting movement relative thereto about transverse and longitudinal axes, an arm structure pivotally mounted upon a substantially upright axis on the forward end of said support for swinging movement relative thereto, a cutter head rotatably mounted on the outer extremity of said arm structure, and a kerf cutter pivotally mounted on said cutter head.
- 35 28. In a mining apparatus, a portable base, a horizontal turntable mounted on said base for rotation relative thereto about a vertical axis, a second turntable mounted on said first turntable for rotation relative thereto and to said base about a parallel axis, a cutter head mounted on said second turntable for rotation relative thereto about a horizontal axis, a kerf cutter pivotally mounted on said cutter head, and a motor mounted on one of said turntables for rotating said turntables about their respective axes, for rotating said cutter head and for swinging said kerf cutter.
- 40 29. In a mining apparatus, a portable base, a horizontal turntable mounted on said base for rotation about a vertical axis and for universal tilting movement relative to the horizontal, said turntable being adjustable in a vertical direction relative to said base, an arm structure pivotally mounted upon a substantially upright axis on said turntable and adjustable therewith and swingable relative thereto, and kerf cutting mechanism carried at the outer extremity of said arm structure and adjustable relative thereto into horizontal and vertical cutting positions.
- 45 30. In a mining apparatus, a portable base, a horizontal turntable mounted on said base for rotation relative thereto about a vertical axis, a second turntable mounted on said first turntable for rotation relative thereto and to said base about a parallel axis, a cutter head mounted on said second turntable for rotation relative thereto about a horizontal axis, a kerf cutter pivotally mounted on said cutter head, and a motor mounted on one of said turntables for rotating said turntables about their respective axes, for rotating said cutter head and for swinging said kerf cutter.
- 50 31. In a mining apparatus, a portable base, a horizontal turntable mounted on said base for rotation relative thereto about a vertical axis, a second turntable mounted on said first turntable for rotation relative thereto and to said base about a parallel axis, a cutter head mounted on said second turntable for rotation relative thereto about a horizontal axis, a kerf cutter pivotally mounted on said cutter head, and a motor mounted on said first turntable and relative to which the second turntable is rotatable for rotating said turntables about their respective axes, for rotating said cutter head and for swinging said kerf cutter.
- 55 32. In a mining apparatus, a movable base, a support mounted on said base for swinging movement relative thereto about a normally vertical axis and also for tilting movement relative to the base, a second support mounted on said first support for swinging movement relative thereto about a parallel axis, a substantially horizontally extending cutter bar, mounting means for the cutter bar in connection with the second support whereby the bar is movable relative to the support about a plurality of rectangularly related axes of which one is substantially on the horizontal, means operable to tilt the first support, means operable to swing both supports about their respective axes, and means operable to move the cutter bar about said plurality of rectangularly related axes.
- 60 33. In a mining apparatus, a movable base, a support mounted on said base for swinging movement relative thereto about a normally vertical axis and also for tilting movement relative to the base, a second support mounted on said first support for swinging movement relative thereto about a parallel axis, a substantially horizontally extending cutter bar, mounting means for the cutter bar in connection with the second support whereby the bar is movable relative to the support about a plurality of rectangularly related axes of which one is substantially on the horizontal.

- zontal, means operable to tilt the first support, means operable to swing both supports about their respective axes, means operable to move the cutter bar about said plurality of rectangularly related axes, and a motor on said first support for driving the support swinging means and the cutter bar moving means.
34. In a mining apparatus, a truck adapted to travel over a mine track, a turntable, means supporting said turntable on said truck for rotation relative to the truck on a normally vertical axis and also for tilting movement relative to the truck, a second turntable mounted on said first turntable for rotation about a parallel axis, an arm fixed to said second turntable and projecting horizontally therefrom, a kerf cutter supported by said arm for movement relative thereto about a plurality of rectangularly related axes of which one is substantially on the horizontal, means operable to tilt said first turntable, means operable to rotate said turntables about their respective axes, and means operable to move the cutter bar about said plurality of rectangularly related axes.
25. In a mining apparatus, a truck adapted to travel over a mine track, a turntable, means supporting said turntable on said truck for rotation relative to the truck on a normally vertical axis and also for tilting movement relative to the truck, a second turntable mounted on said first turntable for rotation about a parallel axis, an arm fixed to said second turntable and projecting horizontally therefrom, a kerf cutter supported by said arm for movement relative thereto about a plurality of rectangularly related axes of which one is substantially on the horizontal, means operable to tilt said first turntable, means operable to rotate said turntables about their respective axes, means operable to move the cutter bar about said plurality of rectangularly related axes, and a motor on the first turntable for driving the turntable rotating means and the cutter bar moving means.
36. In a mining apparatus, a portable base, a support mounted on said base for rotation relative thereto about a vertical axis, a second support mounted on said first support for rotation relative thereto about a parallel axis, said second support overhanging said base, a kerf cutter pivotally mounted on said second support to swing relative thereto about another parallel axis, and motor operated devices for independently rotating said supports about their respective axes.
37. In a mining apparatus, a portable base, a support mounted on said base for rotation relative thereto about a vertical axis, a second support mounted on said first support for rotation relative thereto about a parallel axis, said second support overhanging said base, a kerf cutter pivotally mounted on said second support to swing relative thereto, and motor operated devices for independently rotating said supports about their respective axes and including a motor mounted on one of said supports.
38. In a mining apparatus, a portable base, a support mounted on said base for rotation relative thereto about a vertical axis, a second support mounted on said first support for rotation relative thereto about a parallel axis, said second support overhanging said base, a kerf cutter pivotally mounted on said second support to swing relative thereto, and motor operated devices for independently rotating said supports about their respective axes and including a motor mounted on said first support and relative to which the second support is rotatable for rotating both of said supports.
39. In a mining apparatus, a portable base, a support mounted thereon for swinging movement relative thereto about a vertical axis and for adjustment into different elevated positions relative to said base, a second support mounted on said first support for swinging movement relative thereto about a parallel axis, a kerf cutter, and means for mounting said kerf cutter on said second support for adjustment relative thereto into parallel cutting positions.
40. In a mining apparatus, a portable base, a support mounted thereon for swinging movement relative thereto about a vertical axis and for adjustment into different elevated positions relative to said base, a second support mounted on said first support for swinging movement relative thereto about a parallel axis, a kerf cutter, and means for mounting said kerf cutter on said second support for adjustment relative thereto about a horizontal axis to position said kerf cutter in parallel cutting planes at either side of said horizontal axis.
41. In a mining apparatus, a portable base, a horizontal turntable mounted on said base for rotation relative thereto about a vertical axis and for adjustment into different elevated positions relative to said base, a second turntable mounted on said first turntable for rotation relative thereto and to said base about a parallel axis, a cutter head mounted on said second turntable for rotation relative thereto about a horizontal axis, and a kerf cutter pivotally mounted on said cutter head.
42. In a mining apparatus, a portable base, a support mounted on said base for rotation relative thereto about a vertical axis, a second support mounted on said first support for rotation relative thereto about a parallel axis, said second support overlying said first support and overhanging said base, a kerf cutter pivotally mounted on said second support for swinging movement relative thereto, and motor operated devices for independently rotating said supports about their respective axes.
43. In a mining apparatus, a portable base, a support mounted on said base for rotation relative thereto about a vertical axis, a second support mounted on said first support for rotation relative thereto about a parallel axis, said second support overlying said first support and overhanging said base, a kerf cutter pivotally mounted on said second support for swinging movement relative thereto, and motor operated devices for independently rotating said supports about their respective axes and including a motor mounted on one of said supports.
44. In a mining apparatus, a portable base, a support mounted on said base for rotation relative thereto about a vertical axis, a second support mounted on said first support for rotation relative thereto about a parallel axis, said second support overlying said first support and overhanging said base, a kerf cutter pivotally mounted on said second support for swinging movement relative thereto, and motor operated devices for independently rotating said supports about their respective axes and including a motor mounted on said first support and relative to which the second support is rotatable for rotating both of said supports.
45. In a mining apparatus, a portable base, a horizontal turntable mounted on said base for rotation relative thereto about a vertical axis.

and for adjustment into different elevated positions relative to said base, a rotatable cutter head carrying a pivoted kerf cutter, an adjustable supporting structure on which said cutter head is rotatably mounted, said supporting structure being mounted on said turntable and adjustable relative thereto to position the cutter head laterally relative to said turntable and base, said kerf cutter being rotatable with said head into horizontal and vertical cutting positions, and motor operated devices for rotating said turntable and for adjusting said supporting structure relative to said turntable.

46. In a mining apparatus, a portable base, a horizontal turntable mounted on said base for rotation relative thereto about a vertical axis and for adjustment into different elevated positions relative to said base, a rotatable cutter head carrying a pivoted kerf cutter, an adjustable supporting structure on which said cutter head is rotatably mounted, said supporting structure being mounted on said turntable and adjustable relative thereto to position the cutter head laterally relative to said turntable and base, said kerf cutter being rotatable with said head into horizontal and vertical cutting positions, and motor operated devices for rotating said turntable and for adjusting said supporting structure relative to said turntable, said adjustable supporting structure and said turntable being simultaneously adjustable to position the kerf cutter when in its vertical cutting position in different parallel planes between the sides of said base.

35 47. In a mining apparatus, a portable base, a horizontal support mounted on said base for rotation relative to said base and for universal tilting movement relative to the horizontal, a second horizontal support swingably mounted on said first support, said second support overlying said first support and at its outer extremity overhanging said base, and a kerf cutter mounted on said outer overhanging extremity of said second support and located with its rear extremity wholly in advance of said base.

48. In a mining apparatus, a portable base, a horizontal support mounted on said base for rotation relative to said base and for universal tilting movement relative to the horizontal, a second horizontal support horizontally swingably mounted on said first support, said second support overlying said first support and at its outer extremity overhanging said base, and a kerf cutter mounted on said outer overhanging extremity of said second support, said second support being swingable laterally relative to said first support to position said kerf cutter into different cutting positions to cut parallel spaced apart kerfs between the sides of said base.

60 49. In a mining apparatus, a portable base, a horizontal support mounted on said base for universal tilting movement relative to the horizontal and for horizontal swinging movement, a second horizontal support swingably mounted on said first support for swinging laterally relative thereto, said second support overlying said first support and at its outer extremity overhanging said base, a rotatable cutter head mounted on the outer overhanging extremity of said second support, and a kerf cutter pivotally mounted on said cutter head and adjustable with said head into different cutting positions about the head axis including parallel vertical cutting positions at opposite sides of the head axis.

75 50. In a mining apparatus, a portable base, a

horizontal support mounted on said base for universal tilting movement relative to the horizontal and for horizontal swinging, a second horizontal support swingably mounted on said first support, said second support overlying said first support and at its outer extremity overhanging said base, a rotatable cutter head mounted on the outer overhanging extremity of said second support, and a kerf cutter pivotally mounted on said cutter head and adjustable with said head into different cutting positions about the head axis including parallel vertical cutting positions at opposite sides of the head axis, said second support being swingable relative to said first support on swinging of the latter to position said kerf cutter into different vertical cutting positions parallel with aforesaid vertical cutting positions between the sides of said base.

51. In a mining apparatus, a portable base, a support mounted on said base for tilting movement relative thereto about a horizontal axis and for horizontal swinging movement, a second support mounted on said first support to swing relative thereto about an axis perpendicular to a line parallel to a line parallel to the axis of tilting movement of said first support, said second support overlying said first support and at its outer extremity overhanging said base, and a kerf cutter mounted on the outer overhanging extremity of said second support to swing in a vertical plane relative thereto.

52. In a mining apparatus, a portable base, a support mounted on said base for tilting movement relative thereto about a horizontal axis and for horizontal swinging relative thereto, a second support mounted on said first support to swing relative thereto about an axis perpendicular to a line parallel to a line parallel to the axis of tilting movement of said first support, said second support overlying said first support and at its outer extremity overhanging said base, and a kerf cutter mounted on the outer overhanging extremity of said second support to swing in a vertical plane relative thereto and adjustable therewith laterally relative to said base into different vertical cutting positions parallel with a longitudinally extending vertical plane and aforesaid vertical plane.

53. In a mining apparatus, a portable base, a support mounted on said base for tilting movement relative thereto about a horizontal axis and for horizontal swinging relative thereto, a second support mounted on said first support to swing relative thereto about an axis perpendicular to a line parallel to a line parallel to the axis of tilting movement of said first support, said second support overlying said first support and at its outer extremity overhanging said base, a rotatable cutter head mounted on the outer overhanging extremity of said second support, and a kerf cutter pivotally mounted on said cutter head and adjustable with said head into different cutting positions about the head axis including parallel vertical cutting positions at opposite sides of the head axis, said second support being swingable laterally relative to said first support to move said cutter head to adjust said kerf cutter into different vertical cutting positions parallel with aforesaid vertical cutting positions between the sides of said base.

70 54. In a mining apparatus, a portable base, a horizontal turntable mounted on said base for rotation relative thereto about a vertical axis, a horizontal arm-like support mounted on said turntable to swing relative thereto about an axis

- parallel with the turntable axis, said support overlying said turntable and at its outer extremity overhanging said base, a kerf cutter swingably mounted on the outer overhanging extremity of said second support, and means for rotating said turntable and for swinging said support to move the kerf cutter into parallel cutting positions between the sides of said base.
55. In a mining apparatus, a portable base, a horizontal turntable mounted on said base for rotation relative thereto about a vertical axis, a horizontal arm-like support mounted on said turntable to swing relative thereto about an axis parallel with the turntable axis, said support overlying said turntable and at its outer extremity overhanging said base, a kerf cutter swingably mounted on the outer overhanging extremity of said second support, and means for rotating said turntable and for swinging said support to move the kerf cutter into parallel cutting positions including positions laterally beyond the sides of said base.
56. In a mining apparatus, a portable base, a horizontal turntable mounted on said base for rotation relative thereto about a vertical axis, a horizontal arm-like support mounted on said turntable to swing relative thereto about an axis parallel with the turntable axis, said support overlying said turntable and at its outer extremity overhanging said base, a kerf cutter swingably mounted on the outer overhanging extremity of said second support, and means for rotating said turntable and for swinging said support to move the kerf cutter into parallel cutting positions including positions laterally beyond the sides of said base and a position midway between the sides of said base.
57. In a mining apparatus, a portable base, a support mounted on said base for rotation relative thereto about a vertical axis and for adjustment into different elevated positions relative to said base, a second support mounted on said first support to swing relative thereto about a parallel axis, said second support overlying said first support and at its outer extremity overhanging said base, and a kerf cutter swingably mounted on the outer overhanging extremity of said second support.
58. In a mining apparatus, a portable base, a support mounted on said base for rotation relative thereto about a vertical axis and for adjustment into different elevated positions relative to said base, a second support mounted on said first support to swing relative thereto about a parallel axis, said second support overlying said first support and at its outer extremity overhanging said base, and a cutter head rotatably mounted on the outer overhanging extremity of said second support, and a kerf cutter pivotally mounted on said cutter head and adjustable with said head about the head axis into different cutting positions.
59. In a mining apparatus, a portable base, a kerf cutter swingable relative to said base to cut a vertical kerf, and adjustable supporting means on said base for supporting said kerf cutter and adjustable to move said kerf cutter into parallel vertical cutting positions between the sides of said base and including a plurality of relatively adjustable supports overlying said base in superimposed relation, one mounted on the other, and rotatable relative to the base about parallel vertical axes located at the rear of the forward end of said base and motor operated devices for rotating said supports about their respective axes independently.
60. In a mining apparatus, a portable base, a kerf cutter swingable relative to said base to cut a vertical kerf, and adjustable supporting means on said base for supporting said kerf cutter and adjustable to move said kerf cutter into parallel vertical cutting positions including positions between the sides of said base and laterally beyond the sides of said base and including a plurality of relatively adjustable supports, one mounted in superimposed relation on the other, and rotatable relative to the base about parallel vertical axes, one of said supports overhanging the other, said kerf cutting mounted on said overhanging support and motor operated devices for rotating said supports about their respective axes independently.
61. In a mining apparatus, a portable base, a kerf cutter swingable relative to said base to cut a vertical kerf, and adjustable supporting means on said base for supporting said kerf cutter and adjustable to move said kerf cutter into parallel vertical cutting positions between the sides of said base and including a plurality of relatively adjustable supports, one mounted on the other, said supports rotatable relative to the base about parallel vertical axes, one individual to each, and motor operated devices for rotating said supports about their respective axes independently, one of said supports overlying said base and another support mounted on and overlying the other support and at its forward extremity overhanging said base.
62. In a mining apparatus, a portable base, a kerf cutter swingable relative to said base to cut a vertical kerf, and adjustable supporting means on said base for supporting said kerf cutter and adjustable to move said kerf cutter into parallel vertical cutting positions between the sides of said base and including a plurality of relatively adjustable supports, one mounted in superimposed relation on the other, said supports rotatable relative to the base about parallel vertical axes one individual to each, one support overhanging the other, said kerf cutter mounted on said overhanging support and motor operated devices for rotating said supports independently about their respective axes, said support mounted on the other support being movable, upon rotation of the other support relative to the base, bodily relative to the base to positions from one side of the base to the other.
63. In a mining apparatus, a portable base, a support mounted on said base for rotation relative thereto about a vertical axis, a second support mounted on said first support for rotation relative thereto about a parallel axis lying within the outline of said first support, said second support overlying said first support and overhanging said base, a kerf cutter mounted on the overhanging extremity of said second support and with its rear extremity located wholly in advance of said base, and motor operated devices for independently rotating said supports about their respective axes.
64. In a mining apparatus, a portable base, a support mounted on said base for rotation relative thereto about a vertical axis, a second support mounted on said first support for rotation relative thereto about a parallel axis lying within the outline of said first support, said second support overlying said first support and overhanging said base, a kerf cutter mounted on said second support, and motor operated devices for independently rotating said supports about their respective axes and including a motor mounted

on one of said supports for rotating both supports.

65. In a mining apparatus, a portable base, a support mounted on said base for rotation relative thereto about a vertical axis, a second support mounted on said first support for rotation relative thereto about a parallel axis lying within the outline of said first support, said second support overlying said first support and overhanging said base, a kerf cutter mounted on said second support, and motor operated devices for independently rotating said supports about their respective axes and including a motor mounted on said first support and relative to which the second support is rotatable for rotating both of said supports.

66. In a mining apparatus, a portable base, a support mounted on said base for rotation relative thereto about a vertical axis, a second support mounted on said first support for rotation relative thereto about a parallel axis, said second support overlying said first support and overhanging said base, a kerf cutter mounted on said second support, and motor operated devices for independently rotating said supports about their respective axes and for swinging said kerf cutter relative to said second support.

67. In a mining apparatus, a portable base, a support mounted on said base for rotation relative thereto about a vertical axis, a second support mounted on said first support for rotation relative thereto about a parallel axis, said second support overlying said first support and overhanging said base, a kerf cutter mounted on said second support, and motor operated devices for independently rotating said supports about their respective axes and swinging said kerf cutter relative to said second support, said devices including a motor mounted on one of said supports.

68. In a mining apparatus, a portable base, a support mounted on said base for rotation relative thereto about a vertical axis, a second support mounted on said first support for rotation relative thereto about a parallel axis, said second support overlying said first support and overhanging said base, a kerf cutter mounted on said second support, and motor operated devices for independently rotating said supports about their respective axes and swinging said kerf cutter relative to said second support, said devices including a motor mounted on said first support and relative to which the second support is rotatable for rotating both of said supports.

69. In a mining apparatus, a portable base, a horizontal support mounted on said base for universal tilting movement relative to the horizontal, a second horizontal support swingably mounted on said first support, said second support overlying said first support and at its outer extremity overhanging said base, a rotatable cutter head mounted on the outer overhanging extremity of said second support, and a kerf cutter pivotally mounted on said cutter head and adjustable with said head into different cutting positions about the head axis including parallel vertical cutting positions at opposite sides of the head axis, said supports adjustable horizontally relative to said base to move the kerf cutter into different parallel vertical cutting positions.

70. In a mining apparatus, a portable base, a horizontal support mounted on said base for horizontal rotation and for universal tilting movement relative to the horizontal, a second horizontal support swingably mounted on said first support, said second support overlying said first support and at its outer extremity overhang-

ing said base, a rotatable cutter head mounted on the outer overhanging extremity of said second support, and a kerf cutter pivotally mounted on said cutter head and adjustable with said head into different cutting positions about the head axis including parallel vertical cutting positions at opposite sides of the head axis, said second support being swingable horizontally relative to said first support to position said kerf cutter on rotation of said first support, into different vertical cutting positions between the sides of said base.

71. In a mining apparatus, a portable base, a support mounted on said base for tilting movement relative thereto about a horizontal axis and for horizontal swinging relative thereto, a second support mounted on said first support to swing relative thereto about an axis perpendicular to the axis of tilting movement of said first support, said second support overlying said first support and at its outer extremity overhanging said base, and a kerf cutter mounted on the outer overhanging extremity of said second support to swing in a vertical plane relative thereto, said supports swingable horizontally relative to said base to move the kerf cutter to swing in parallel vertical planes parallel with aforesaid vertical plane.

72. In a mining apparatus, a portable base, a support mounted on said base for tilting movement relative thereto about a horizontal axis and for horizontal swinging relative thereto, a second support mounted on said first support to swing relative thereto about an axis perpendicular to a line parallel to a line parallel to the axis of tilting movement of said first support, said second support overlying said first support and at its outer extremity overhanging said base, and a kerf cutter mounted on the outer overhanging extremity of said second support to swing in a vertical plane relative thereto and adjustable therewith laterally relative to said base, said kerf cutter adjustable horizontally with said supports into parallel vertical planes parallel with aforesaid vertical plane.

73. In a mining apparatus, a portable base, a support mounted on said base for horizontal swinging and for tilting movement relative thereto about a horizontal axis, a second support mounted on said first support to swing relative thereto about an axis perpendicular to the axis of tilting movement of said first support, said second support overlying said first support and at its outer extremity overhanging said base, a rotatable cutter head mounted on the outer overhanging extremity of said second support, and a kerf cutter pivotally mounted on said cutter head and adjustable with said head into different cutting positions about the head axis including parallel vertical cutting positions at opposite sides of the head axis, said second support being swingable laterally relative to said first support to move said cutter head to adjust said kerf cutter into different vertical cutting positions parallel with aforesaid vertical cutting positions and between the sides of said base.

74. In a mining apparatus, a portable base, a kerf cutter swingable relative to said base to cut a vertical kerf, and adjustable supporting means on said base for supporting said kerf cutter and adjustable to move said kerf cutter into parallel vertical cutting positions between the sides of said base and including a plurality of relatively adjustable supports, one mounted on the other and rotatable relative to the base about parallel

vertical axes and motor operated devices having a driving motor carried on one of said supports for independently rotating said supports about their respective axes, either support swingable relative to the other while the latter remains stationary as regards swinging movement about its own axis.

75. In a mining apparatus, a portable base, a kerf cutter swingable relative to said base to cut a vertical kerf, and adjustable supporting means on said base for supporting said kerf cutter and adjustable to move said kerf cutter into parallel vertical cutting positions including positions between the sides of said base and laterally beyond the sides of said base and including a plurality of relatively adjustable supports, one mounted on the other, and rotatable relative to the base about parallel vertical axes and motor operated devices having a driving motor carried on one of said supports for independently rotating said supports about their respective axes, either support swingable relative to the other while the latter remains stationary as regards swinging movement about its own axis.

25. 76. In a mining apparatus, a portable base, a kerf cutter swingable relative to said base to cut a vertical kerf, and adjustable supporting means on said base for supporting said kerf cutter and adjustable to move said kerf cutter into parallel vertical cutting positions between the sides of said base and including a plurality of relatively adjustable supports, one mounted on the other, and rotatable relative to the base about parallel vertical axes and motor operated devices having a driving motor carried on one of said supports for independently rotating said supports about their respective axes, either support swingable relative to the other while the latter remains stationary as regards swinging movement about its own axis and said support mounted on the other support being movable, upon rotation of the other support relative to the base, bodily relative to the base to positions from one side of the base to the other.

45. 77. In a mining apparatus, a portable base, a horizontal support mounted on said base for rotation relative to said base upon a normally upright axis and for universal tilting movement relative to the horizontal, a second horizontal support swingably mounted on said first support to swing relative thereto, said second support overlying said first support and at its outer extremity overhanging said base, and a pivoted kerf cutter mounted on said second support with its pivot located at the outer overhanging extremity of said second support in advance of said base.

50. 78. In a mining apparatus, a portable base, a horizontal support mounted on said base for rotation relative to said base upon a normally upright axis and for universal tilting movement relative to the horizontal, a second horizontal support swingably mounted on said first support to swing relative thereto, said second support overlying said first support and at its outer extremity overhanging said base, and a kerf cutter mounted on said outer overhanging extremity of said second support to swing in vertical planes relative thereto.

55. 79. In a mining apparatus, a portable base, a horizontal support mounted on said base for rotation relative to said base upon a normally upright axis and for universal tilting movement relative to the horizontal, a second horizontal support swingably mounted on said first support

to swing relative thereto, said second support overlying said first support and at its outer extremity overhanging said base, and a kerf cutter mounted on said outer overhanging extremity of said second support to swing in vertical planes relative thereto, said second support being swingable laterally relative to the first support to position said kerf cutter into different parallel vertical cutting positions between the sides of said base.

60. 80. In a mining apparatus, a portable base, a horizontal support mounted on said base for rotation relative to said base upon a normally upright axis and for universal tilting movement relative to the horizontal, a second horizontal support swingably mounted on said first support to swing relative thereto, said second support overlying said first support and at its outer extremity overhanging said base, a kerf cutter mounted on the outer overhanging extremity of said second support, and a motor mounted on one of said supports for rotating said first support and for swinging said second support.

65. 81. In a mining apparatus, a portable base, a horizontal support mounted on said base for rotation relative to said base upon a normally upright axis and for universal tilting movement relative to the horizontal, a second horizontal support swingably mounted on said first support to swing relative thereto, said second support overlying said first support and at its outer extremity overhanging said base, a kerf cutter mounted on said outer overhanging extremity of said second support, said second support being swingable laterally relative to said first support to swing said kerf cutter into different cutting positions between the sides of said base, and a motor mounted on one of said supports for rotating said first support and for swinging said second support.

70. 82. In a mining apparatus, a portable base, a support mounted on said base for rotation relative thereto about a vertical axis, a second support mounted on said first support for rotation relative thereto about a parallel axis lying within the outline of said first support, said second support overlying said first support and overhanging said base, a kerf cutter mounted on said second support to swing in vertical planes relative thereto, and motor operated devices for independently rotating said supports about their respective axes.

75. 83. In a mining apparatus, a portable base, a support mounted on said base for rotation relative thereto about a vertical axis, a second support mounted on said first support for rotation relative thereto about a parallel axis lying within the outline of said first support, said second support overlying said first support and overhanging said base, a kerf cutter mounted on the overhanging extremity of said second support with its rear extremity located wholly in advance of said base, and motor operated devices for independently rotating said supports about their respective axes and including a motor mounted on one of said supports.

80. 84. In a mining apparatus, a portable base, a support mounted on said base for rotation relative thereto about a vertical axis, a second support mounted on said first support for rotation relative thereto about a parallel axis lying within the outline of said first support, said second support overlying said first support and overhanging said base, a kerf cutter mounted on the overhanging extremity of said second support for swinging movement relative thereto, and motor

operated devices for independently rotating said supports about their respective axes.

85. In a mining apparatus, a portable base, a support mounted on said base for rotation relative thereto about a vertical axis, a second support mounted on said first support for rotation relative thereto about a parallel axis lying within the outline of said first support, said second support overlying said first support and overhanging said base, a kerf cutter mounted on said second support for swinging movement relative thereto, and motor operated devices for independently rotating said supports about their respective axes and including a motor mounted on 10 one of said supports.

86. In a mining apparatus, a portable base, a support mounted on said base for rotation relative thereto about a vertical axis, a second support mounted on said first support for rotation relative thereto about a parallel axis lying within the outline of said first support, said second support overlying said first support and overhanging said base, a kerf cutter pivotally mounted on the outer overhanging extremity of said second support for swinging movement relative thereto about an axis located a substantial distance in advance of said base, and motor operated devices for independently rotating said supports about their respective axes and including a motor mounted on one of said supports.

87. In a mining apparatus, a portable base, a support mounted on said base for rotation relative thereto about a vertical axis, a second support mounted on said first support for rotation relative thereto about a parallel axis lying within the outline of said first support, said second support overlying said first support and overhanging said base, a kerf cutter mounted on said second support to swing in vertical planes, and motor operated devices for independently rotating said supports about their respective axes.

88. In a mining apparatus, a portable base, a

support mounted on said base for rotation relative thereto about a vertical axis, a second support mounted on said first support for rotation relative thereto about a parallel axis lying within the outline of said first support, said second support overlying said first support and overhanging said base, a kerf cutter mounted on said second support to swing in vertical planes, and motor operated devices for independently rotating said supports about their respective axes and including a motor mounted on one of said supports.

89. In a mining apparatus, a portable base, a turntable mounted for rotation on said base and for adjustment vertically relative thereto, an arm structure mounted on and overlying said turntable, said arm structure swingable relative to said turntable, and a rotatable cutter head mounted on the outer overhanging extremity of said arm structure and carrying a kerf cutter.

90. In a mining apparatus, a portable base, a rotatable turntable mounted on said base for universal tilting movement relative thereto, an arm structure mounted on and overlying said turntable, said arm structure swingable horizontally relative to said turntable, and a rotatable cutter head mounted on the outer overhanging extremity of said arm structure and carrying a kerf cutter.

91. In a mining apparatus, a portable base, a support mounted on said base for tilting movement relative thereto about a horizontal axis, an arm structure pivotally mounted upon a substantially upright axis on the forward end of said support for swinging movement relative thereto, said arm structure being adjustable horizontally relative to said base, a cutter head rotatably mounted on the outer extremity of said arm structure, and a kerf cutter pivotally mounted on said cutter head.

LOUIS A. MAXSON.
